(57) CLAIM

The ornamental design for a shoe case, as shown and described.

DESCRIPTION

FIG. 1 is a front view of a shoe case showing my new design;

FIG. 2 is a rear view thereof;

FIG. 3 is a side view thereof;

FIG. 4 is an opposite side view thereof;

FIG. 5 is a top view thereof;

FIG. 6 is a bottom view thereof;

FIG. 7 is a perspective view thereof;

FIG. 8 is a front view of a shoe case in an open position showing my new design;

FIG. 9 is a rear view thereof;

FIG. 10 is a side view thereof;

FIG. 11 is an opposite side view thereof;

FIG. 12 is a top view thereof;

FIG. 13 is a bottom view thereof;

FIG. 14 is a perspective view thereof;

FIG. 15 is a front view of a shoe case in an open position showing my new design;

FIG. 16 is a rear view thereof;

FIG. 17 is a side view thereof;

FIG. 18 is an opposite side view thereof;

FIG. 19 is a top view thereof;

FIG. 20 is a bottom view thereof; and,

FIG. 21 is a perspective view thereof.

The broken lines illustrate environmental subject matter which forms no part of the claimed design.
